(57) **CLAIM**

The ornamental design for tablet case and stand, as shown and described.

DESCRIPTION

FIG. 1. is a front perspective view of a tablet case and stand showing the new design;

FIG. 2 is a front view thereof, showing adjustment of the bracket;

FIG. 3 is a rear perspective view thereof;

FIG. 4 is a top view thereof;

FIG. 5 is bottom view thereof;

FIG. 6 is a left view thereof;

FIG. 7 is right view thereof;

FIG. 8 is a rear plan view thereof;

FIG. 9 is an exploded rear view of the bottom left corner of the tablet case with the locked cover removed, exposing a mechanism for adjusting the bracket; and,

FIG. 10 is a rear perspective view thereof, with a portion of the vertical support cut out to show the rear lock housing.

The broken lines in the figures illustrate unclaimed environment and form no part of the claimed design.
